UNITED STATES PATENT OFFICE

160,320

GYMNASIUM AND PLAYGROUND
APPARATUSIsadore Horowitz, Shreveport, La., assignor to
Universal Manufacturing Company, Bossier,
La.

Application October 24, 1949, Serial No. 5,666

Term of patent 14 years

(Cl. D34—5)

To all whom it may concern:

Be it known that I, Isadore Horowitz, a citizen of the United States, residing at Shreveport, in the parish of Caddo and State of Louisiana, have invented a new, original, and ornamental Design for a Gymnasium and Playground Apparatus, of which the following is a specification, reference being had to the accompanying drawing, forming part thereof.

The single figure is a perspective view of the gymnasium and playground apparatus, showing my new design.

I claim:

The ornamental design for a gymnasium and playground apparatus, as shown,

ISADORE HOROWITZ.
